UNITED STATES PATENT OFFICE.

RALPH C. CUNNINGHAM, OF TACOMA, WASHINGTON.

GAME-PIECE SUPPORT.

Application filed December 28, 1922. Serial No. 408,790.

To all whom it may concern:

Be it known that I, RALPH C. CUNNINGHAM, a citizen of the United States of America, and resident of the city of Tacoma, in the county of Pierce and State of Washington, have invented certain new and useful Improvements in Game-Piece Supports, of which the following is a specification.

My invention is particularly intended for use when playing such games as mah jongg, pung chow, dominoes, or the like, in which the game pieces are tiles or blocks printed upon one side and intended to be stood upon an end or edge.

When such blocks stand on end or on their sides, it is difficult to see them if placed upon a table close to the player, and yet if they are placed at a sufficient distance so that the angle of vision permits them to be seen easily, they become visible to another player at either side of their possessor.

It is an object of my invention to provide a support for such game pieces which will maintain them at an angle at which they can readily be seen by their possessor, and yet at such an angle, or otherwise concealed, so that they may not readily be seen by an opposing player at the side of the first player.

A further object is the provision of such a game-piece support which is easily and cheaply manufactured.

My invention comprises the novel support and the construction and relative arrangement of parts thereof which are shown in the accompanying drawings, described in the specification and particularly defined by the claim terminating the same.

In the accompanying drawing, Figure 1 is a perspective view of the support.

Figure 2 is a cross section of the same.

In the game of mah jongg or pung chow, as it is variously called, for which my device is particularly intended, it is necessary to build a line or wall of thirty-four game-pieces or tiles piled two deep, and then to move this wall forward to a common center. My invention, comprising a strip somewhat after the fashion of molding strips, is useful as a ruler to move forward this wall. For this purpose its back 1, which would generally, although not necessarily, be at right angles to its bottom or base 2, is employed, the back 1 standing at a height

generally more than twice the thickness of the tile or game-piece 3.

The strip is, of course, as long as may be desired. It is formed with a slanting surface 4 which at its lower end meets a ledge 5, which may be a surface at right angles to the surface 4. The surface 4 supports the tile 3, the lower end of the tile resting against the ledge 5. It is thus held in proper position. The angle of the surface 4 is of some importance. I have found that a desirable angle is about 50° from the horizontal. At a lesser angle to the horizontal the pieces 3 become easily visible to a player at one side of the possessor of the piece, while if the angle is considerably greater than this the pieces are not readily visible to their possessor. If this angle is to be varied, however, it is more desirable to increase than to decrease the angle of the surface 4 with the horizontal. It will be noted from the drawings that the extent of the surface 4 is less than the length of a tile 3, and hence it is possible easily to pick up any tile which the possessor may desire to play, or to pick up a plurality of tiles simultaneously.

It will be noted that the support illustrated herein may be formed from a strip of wood by a simple coping hand, just as molding strips are cut. The surface 4 is preferably at right angles to the surface 5. The support can therefore be simply and cheaply manufactured. Further, the device is one which is practical in use. It supports pieces which are ordinarily difficult to maintain upright, and as one of these sticks is provided for each player and may be moved about and placed at any position he may desire in front of him, and is not connected with a support maintained by any other player, the device is one which will really assist the player.

In the playing of the games of mah jongg, pung chow, dominoes or the like the block like game pieces 3 that are left in the hands of the players at the completion of the playing of a "hand" must be exhibited for counting. The structure of Fig. 2 is of particular utility in thus exhibiting the remaining pieces to all the other players since this may be accomplished by merely tipping the support or holder over, rearwardly, so that it will rest upon its back 1. The game pieces may be left exposed and in an inclined position, until the counting is

completed after which they may be completely discharged from the molding or strip by merely withdrawing the strip from beneath them leaving them in position to be 5 mixed and shuffled with the remaining game pieces preparatory to continuing the play. This capability of discharging the block like game pieces by tipping the support rearwardly and then drawing the same bodily forward and from beneath the game pieces arises from the fact that the inclined supporting face 4 is free and unobstructed. In other words the game pieces are not held in engagement therewith other than by 10 gravity and consequently they may be readily tipped out of engagement therewith as described. By referring to Fig. 2 it will be seen that the upper rear edge of the molding is beveled off, as indicated at 1^a. This 15 renders it possible to have the game pieces project enough beyond the upper limit of the slanting surface 4 to be readily engageable by the fingers while at the same time the length of the game pieces will not exceed the length of the upper side of the angle constituted by the rear wall 1 and the 20 surface 4. If the game pieces project materially beyond the plane of rear wall 4 it would not be possible to tip the support 25 rearwardly, as described, with facility, because the corners of the game pieces would engage the table before the completion of the tipping action. Thus it will be seen that in order to insure the full measure of 30 advantage outlined, a device of this nature must,

First; be capable of economical manufacture.

Second; present a pleasing and ornamental appearance.

Third; hold game pieces of block like

shape in such position that they will be visible to the player and will not be visible to his opponent.

Fourth; be free and unobstructed at its front face to permit bodily gravity discharge of the block like game pieces upon rearward tipping of the support.

Fifth; be of such dimensions with respect to the dimensions of the game pieces as to cause said game pieces to project beyond the upper rear edge thereof while at the same time said game pieces will lie wholly inwardly of the plane of the rear wall of the support.

What I claim as my invention is:

In combination a plurality of block like game pieces and a support for the same comprising an elongated strip having a horizontal bottom, a substantially vertical rear wall, a supporting ledge along the forward edge of said strip and a supporting surface inclined rearwardly and upwardly from said ledge toward the rear side of the strip, the upper rear edge of the strip being beveled off and the length of the game pieces being such with respect to the width of the inclined supporting surface that the upper ends of said game pieces project beyond said supporting surface but lie within the vertical plane of the rear wall of the strip, whereby the projecting portions of a plurality of the game pieces may be simultaneously grasped to lift and play them and whereby the elongated strip may be tipped over rearwardly without interference by the said game pieces, to expose the said game pieces to the view of other players.

Signed at Seattle, King County, Washington, this 21st day of December 1922.

RALPH C. CUNNINGHAM.
